UNITED STATES PATENT OFFICE.

WALTER F. MARKS, OF CHAPINVILLE, NEW YORK.

VARIABLE SPEED DEVICE.

SPECIFICATION forming part of Letters Patent No. 297,143, dated April 22, 1884.

Application filed September 6, 1883. (No model.)

To all whom it may concern:

Be it known that I, WALTER F. MARKS, of Chapinville, Ontario county, New York, have invented an Improved Variable Speed Device, 5 of which the following is a specification, reference being had to the accompanying drawings.

My invention relates to an improved variable speed device designed for use in connection with grain-drills, but capable of being applied to many other purposes, which improvement is hereinafter fully described and specified.

My improved variable speed device is represented in the accompanying drawings, in which Figure 1 is a plan view. Fig. 2 is a side elevation. Fig. 3 is a diagram illustrating the variable motion of the clutch-levers. Fig. 4 is a plan view of a modification. Fig. 20 5 is a side elevation of the same. Fig. 6 represents a modified form of the cams.

In the accompanying drawings, A represents the driving-shaft of the clutch mechanism, provided with two or more cams or eccentric, D D, which impart a vibrating motion to the clutch-levers E E as the shaft revolves, and B is the driven shaft, to which are secured the clutch-disks F F, having the grooves G in their sides, in which the dogs H, 25 connected with the levers E E, engage. The levers E E are made of such a length as to permit the shafts A and B to be shifted relatively to each other without bringing the cams D D beyond the ends of the levers. By shortening 30 the distance between these two shafts, the angular vibration imparted to the levers by the cams on the shaft A will be increased, while by removing the shafts to a greater distance apart the throw of the levers will be decreased, 35 and in this way the speed of the rotation of the driven shaft may be varied. This operation is illustrated by the diagram, Fig. 3. When the cam or eccentric D is placed away from the driven shaft B, the vibration of the 40 lever E will be from E to E', Fig. 3; but when it is brought nearer to B, the lever will vibrate from E to E". The levers E swing freely about the driven shaft, being allowed to fall by their own weight, or they may be provided with 45 springs, by which their return movement is secured. The dogs H are provided with lat-

erally-projection lugs o, which engage with the grooves G in the side of the clutch-disks F, so that when the levers rise their motion is imparted to the disks and the driven shaft; 55 but when the levers descend, the lugs slide within the grooves. The outer ends of the dogs are provided with slots, through which pass the screws or pins P, inserted in the side of the levers. Springs I, attached to the levers in any suitable manner, press against the upper sides of the dogs. The cams on the shaft A may be of any suitable form, that illustrated in Fig. 6 being adapted for use when only two cams, clutches, and clutch-levers are 60 employed, in which case it is desirable to secure a quick return movement of the levers, so that a continuous rotation may be imparted to the driven shaft.

In the drawings I have represented the 70 driven shaft B as arranged to rotate in fixed bearings indicated by the dotted lines T, while the driving-shaft A is shown as arranged to be moved to and from the driven shaft by swinging on the supporting-arm Q, or sliding 75 in the groove O in the supporting-frame K; but it is obvious that either shaft may be adjusted so as to accomplish the result of transmitting a variable rotation to the driven shaft.

In the construction shown in Figs. 1 and 2 80 the shaft C rotates in fixed bearings and transmits motion to the adjustable shaft A by means of the gearing U V, or by suitable belting, the shaft A being supported on the swinging arm or arms Q, connected together by brace or 85 sleeve R, and constructed so as to maintain the two shafts at the same distance apart, while A is capable of being moved to and from the driven shaft B. The same result may be accomplished by allowing the shaft A to slide 90 backward and forward in a groove, O, which may be curved, if desired, in a suitable supporting-frame, K. A lever, N, attached to a yoke-frame, L, connected with the ends of the shaft A, serves to effect its adjustment relatively to the driven shaft. The lever may be provided with a spring-catch engaging with a notched segment in order to secure the shaft A in any desired position. Any suitable form of clutch may be used in connection with my 95 improved variable speed device.

In the drawings the driving-shaft A is rep-

resented in full lines in the position which it occupies when nearest the driven shaft, and in dotted lines A' when at its greatest distance therefrom. The rate of the rotation of the driven shaft will decrease as the shaft A is removed from the shaft B.

I claim—

1. The combination, with the driving and driven shafts A and B, of a series of two or 10 more clutches and clutch-levers applied to the driven shaft, and mechanism for imparting variable motion to the levers, substantially as and for the purposes set forth.

2. The combination, with the relatively adjustable driving and driven shafts A and B, of a series of two or more clutches and clutch-levers applied to the driven shafts, and mechanism for imparting variable motion to the levers, substantially as and for the purposes set 20 forth.

3. The combination, with the shafts C and B, of the intermediate adjustable shaft, A, a series of clutches and clutch-levers applied to the driven shaft B, and mechanism attached 25 to the intermediate shaft to impart variable motion to the clutch-levers, substantially as and for the purposes set forth.

4. The combination, with the shaft A, provided with cams or eccentrics D D, supporting-arm Q, shaft C, and gears U V, of the 30 driven shaft B, arranged to be rotated at a variable speed by clutches and clutch-levers operated from the shaft A, substantially as and for the purposes described.

5. The combination, with the relatively adjustable driving and driven shafts A and B, of a series of clutches and clutch-levers applied to the driven shaft, and a corresponding series of cams on the driving-shaft, and the shaft C, arranged to transmit motion to the 40 driving-shaft by connecting mechanism, substantially as and for the purposes set forth.

6. The combination, with the driven shaft B, arranged to revolve in fixed bearings, and provided with a series of clutches and clutch-levers, of the adjustable driving-shaft A, arranged to be moved to and fro to vary the 45 movement of the clutch-levers, substantially as and for the purposes set forth.
